Sam'l L. Denney, Jr.
Inventor, art.

United States Patent Office.

SAMUEL L. DENNEY, OF CHRISTIANA, PENNSYLVANIA.

Design No. 4,919, dated May 23, 1871.

DESIGN FOR A MEDAL.

The Schedule referred to in these Letters Patent and making part of the same.

To all whom it may concern:

Be it known that I, SAMUEL L. DENNEY, of Christiana, in the county of Lancaster and State of Pennsylvania, have invented new and original Design for a Medal; and I do hereby declare that the following is a full and exact description of the same, reference being had to the accompanying drawing and to the letters of reference marked thereon.

The nature of my design is fully represented in the accompanying drawing, to which reference is made.

The lower half of the medal is occupied by the representation of a locomotive, tender, and car crossing a suspension-bridge spanning a river, the bridge also serving as a support to a number of telegraph-wires.

The upper half of the medal is occupied by words and lines, as follows:

Near the upper edge, in bold letters, are the words "Men of Progress." Below these words a blank line is drawn transversely across the medal, and below this is located the word "Inventor," with a flourish at each end.

What I claim, and desire to secure by Letters Patent, is—

The design for medal, as shown.

SAMUEL L. DENNEY.
